(57) **CLAIM**

I claim the ornamental design for a area light, as shown and described.

DESCRIPTION

FIG. 1 is a front perspective view of my area light.

FIG. 2 is a back perspective view thereof.

FIG. 3 is a back plan view thereof.

FIG. 4 is a front plan view thereof.

FIG. 5 is a left plan view thereof.

FIG. 6 is a right plan view thereof.

FIG. 7 is a top plan view thereof.

FIG. 8 is a bottom plan view thereof; and,

FIG. 9 is a front perspective view thereof with its supporting bracket rotated.

The broken lines show portions of the article not claimed and form no part of the claimed design.
